(57) **CLAIM**

The ornamental design for a dual shower head assembly, as shown and described.

DESCRIPTION

FIG. 1 is a perspective view of a dual shower head assembly showing the new design;

FIG. 2 is another perspective view thereof;

FIG. 3 is a front elevation view thereof;

FIG. 4 is a back elevation view thereof;

FIG. 5 is a left-side elevation view thereof;

FIG. 6 is a right-side elevation view thereof;

FIG. 7 is a top plan view thereof; and

FIG. 8 is a bottom plan view thereof.

FIG. 9 is an enlarged view of the encircled portion in FIG. 1.

FIG. 10 is an enlarged view of the encircled portion in FIG. 1.

FIG. 11 is an enlarged view of the encircled portion in FIG. 2.

FIG. 12 is an enlarged view of the encircled portion in FIG. 2; and,

FIG. 13 is an enlarged view of the encircled portion in FIG. 2.

The equal-length broken lines depict portions of the dual shower head assembly that form no part of the claimed design.

The dash-dot lines in FIG. 1, FIG. 2, FIG. 9, FIG. 10, FIG. 11, FIG. 12, and FIG. 13 illustrate the boundaries of the enlarged view indicators and form no part of the claimed design.

1 Claim, 13 Drawing Sheets
